WHEEL-EQUIPPED SUITCASE
Charles Leavell, 206 S. Fairfield Ave., Lombard, Ill.
Filed Aug. 23, 1962, Ser. No. 220,591
10 Claims. (Cl. 190—18)

This invention relates to a portable container structure, and more particularly to a portable container structure adapted to be manually carried as exemplified by a suitcase or by a trunk.

Some of the suitcases and certain of the trunks now in use are relatively large and are quite heavy when loaded. For example, such portable containers may be used by salesmen to transport their merchandise or display samples; by travelers to transport clothing apparel, etc.; and in many instances, customized containers are constructed to accommodate particular articles or materials; but in any event, the loaded containers whatever their use are heavy and consequently are difficult to carry even though they are equipped with handles for such purpose. Furthermore, if the container is relatively large in addition to being heavy, the problems involved in manual manipulation thereof are amplified.

All of these problems have been understood for some time, and efforts have been made to equip such portable containers with rollers so that in the majority of instances they can be rolled rather than carried. However, the prior efforts in this respect have been wholly unsatisfactory for the most part, for the reasons that the rollers have been in the nature of casters, and since of small diameter do not afford a good rolling action especially over irregular surfaces; the rollers have been detachable units which must be strapped or otherwise secured to the container when it is desired to roll the same, but otherwise must be removed therefrom to prevent damage to other containers during storage or vehicle transport; and such roller units have been unsightly, thereby seriously detracting from the otherwise esthetic appearance of the container.

I recognize the desirability of equipping suitcases and other portable containers of the same general type with a wheel arrangement to permit such containers to be rolled rather than carried during manual transport thereof, but also appreciate the inadequacies of the arrangements heretofore proposed; and, accordingly, state that an object of the present invention is to provide a wheel-equipped, portable container that obviates the aforesaid deficiencies present in prior art arrangements.

Another object of the invention is that of providing a portable container permanently equipped with wheels which do not interfere with normal storage and vehicle transport of such container and which do not, consequently, damage containers stored adjacent thereto. Still another object of the invention is in the provision of a wheel-equipped container structure having wheels of relatively large diameter which, therefore, permit the container to be readily rolled over irregular surfaces.

Yet another object of the invention is to equip a manually portable container with wheels oriented and disposed in a manner such that they are almost entirely concealed and, therefore, do not mar the continuity and uniformity of the container or generally impair the esthetic appearance thereof. Yet a further object is that of providing a suitcase, or other manually portable container, having rounded corners with a pair of wheels respectively located adjacent the transversely aligned corners at one end of the container; the radius of each such wheel being approximately equal to the radius of curvature of each such transversely aligned corner, and the axes of rotation of the wheels being respectively oriented at about the origin of the radius of the corner associated therewith

2

to provide a restricted circumferential area of each wheel for engagement with a support surface to enable the container to be rolled therealong—the dimensional relationship of the wheels and container corners being so determined that the wheels blend into the contours of the container yet have a relatively large diameter so that a good rolling action is afforded over a rough or irregular support surface.

A further object is in providing the combination of a wheel-equipped container of the character described having rounded corners, and in which the wheels comprise a pair thereof respectively mounted interiorly of the container adjacent two of the transversely spaced corners thereof and within dust-proof compartments therefor; each of the wheels having a radius that corresponds essentially to the radius of curvature of the associated corner and being located so that the axis of rotation of each wheel is substantially coextensive with the origin of the radius of curvature of the related corner; the container having a slot or opening extending along each of such corners in alignment with the wheel therein so that a portion thereof occupies the opening and is adapted to rollingly engage a support surface, and essentially replaces the container segments removed in providing the openings, whereby such ground-engaging portions of each wheel form a continuation of the container edges and are then inconspicuous and substantially concealed. Additional objects and advantages of the invention will become apparent as the specification proceeds.

Embodiments of the invention are illustrated in the accompanying drawings, in which—

FIGURE 1 is a side view in elevation of a suitcase embodying the invention;

FIGURE 2 is an enlarged, fragmentary vertical sectional view taken along the line 2—2 of FIGURE 1, but in which a wall portion of the suitcase is broken away to show the wheel construction and mounting thereof;

FIGURE 3 is an enlarged, fragmentary side view in elevation of the lower corner portion of the suitcase as illustrated in FIGURE 1;

FIGURE 4 is an enlarged, broken vertical sectional view taken along the line 4—4 of FIGURE 2;

FIGURE 5 is a further enlarged, perspective view of the corner portion of the suitcase illustrated in FIGURE 4, and in which the various components are arranged in spaced-apart configuration;

FIGURE 6 is a broken front view in elevation generally similar to that of FIGURE 2, but showing a modified construction;

FIGURE 7 is a broken front view in elevation generally similar to that of FIGURE 2, but showing a further modification; and

FIGURE 8 is a broken front view in elevation generally similar to that of FIGURE 2, illustrating yet another modification.

A portable container embodying the invention is exemplified in the drawings in the form of a suitcase which is denoted generally with the numeral 10. To a great extent, the suitcase 10 may be of conventional construction and has two sections 11 and 12 that are secured to each other by hinges (not shown). The sections 11 and 12 are adapted to meet along a perimetric line 13, as shown in FIGURE 2, to define a closed compartment 14 therewithin. Access is afforded to the compartment 14 when the sections 11 and 12 are opened or swung apart about the hinge connections thereof in the usual manner. As seen in FIGURE 1, the suitcase 10 may be equipped with latches 15 and 16 to lock the sections 11 and 12 in the closed position thereof, with a handle 17 along the top thereof, and preferably with a handle-like strap assembly 18 at one end that enables the suitcase to be hand-held at that end. The strap assembly

18 may be of well known construction, as where the strap is longitudinally slidable through spaced-apart, inverted U-shaped guides 19 and 20, but in which such longitudinal movement is limited in each direction by enlarged ends 21 and 22 provided by the strap. Thus, the strap may be flattened against the surface of the suitcase or may be drawn outwardly, as shown in FIGURE 1, between the guides 19 and 20.

For purposes of the present invention, the suitcase may be regarded in its entirety rather than in terms of the sections 11 and 12 thereof; and so considered, has side walls 23 and 24, end walls 25 and 26, a bottom wall 27 and a top wall 28. The suitcase 10 has a trim strip or band running perimetricaly along the axis defined by the juncture of the end, top and bottom walls with respective side walls 23 and 24, and such trim strips are denoted respectively with the numerals 29 and 30. The trim strips are stitched or ornamented with stitch lines 31 and 32 with respect to the strip 29, and 33 and 34 with respect to the strip 30. Further, the corners of the suitcase are arcuate or are rounded, and such rounding occurs along the common line of meeting or juncture between the respective end walls 25 and 26 and bottom and top walls 27 and 28. For purposes of the present invention, two of the corner portions of the suitcase are of importance, and for identification such corners are denoted respectively with the numerals 35 and 36.

As is most apparent from FIGURES 4 and 5, the corner portions 35 and 36 are slotted along the marginal edges thereof defined by the trim strips 29 and 30, and a wheel is mounted within each of these corner portions so that an area thereof projects through the slots for surface engagement to rollingly support the suitcase thereon, and the wheels are respectively designated with the numerals 37 and 38. The construction of the corner portions 35 and 36 and the mounting of the respective wheels 37 and 38 therein are identical, and therefore in the further description of the invention, only the corner portion 35 will be considered in detail, and it will be understood that an identical structural composition is characteristic of the corner portion 36.

The slot or channel through which the wheel 37 projects is indicated with the numeral 39, and the ends thereof are defined by reinforcing strips 40 and 41 secured, respectively, to the end wall 25 and bottom wall 27. The reinforcing strips have end portions 42 and 43, respectively, that are offset slightly by the thickness of the respective end and bottom walls 25 and 27 so as to form essentially continuations thereof when the offset end portions are positioned in overlying juxtaposition with the end and bottom walls of the suitcase. The same reinforcing strips have slightly offset and tapered ends 44 and 45, respectively, that define the actual limits of the slot 39, and the trim strip 29 is beveled slightly to conform to the tapered configuration of the ends 44 and 45. The reinforcing strips 40 and 41 are secured to the associated walls of the suitcase and also to the trim strip 29 by any suitable and appropriate means, which will depend to some extent on the construction of the suitcase. That is to say, the reinforcing strips may be welded, riveted, adhesively bonded, etc. to the suitcase walls and trim strip.

Secured to the side wall 23 is a mounting plate 46 having a laterally and inwardly extending flange 47. The plate 46, and more particularly the flange 47 thereof, has a curvature such that it extends between the reinforcing strips 40 and 41 and terminates in abutment therewith. The plate 46 has a shaft seat or aperture 48 centrally disposed therein adapted to receive an end portion of an axle or shaft 49 that extends through the hub 50 of the wheel 37 and rotatably supports the same therein. If desired, the wheel 37 may be equipped with anti-friction bearings to implement the free rotation thereof about the axle 49. A corresponding mounting plate 51 is adapted to support the opposite end of the axle 49,

and for such purpose is provided with a support opening or aperture 52 that receives such opposite end portion of the axle therein. The axle 49 must be constrained against axial displacement with respect to the mounting plates 46 and 51 and such displacement may be prevented by any suitable means, such as by a cap 53 that extends over the aperture 52 and is welded or otherwise anchored to the mounting plate 51.

The mounting plate 51 is equipped with a laterally and outwardly extending flange 54 having an arc of curvature which corresponds with that of the flange 46, and is adapted to overlie the same as shown most clearly in FIGURE 2. Preferably, the flange 54 is offset centrally so that the outermost portion thereof extends over and along the surface of the flange 47, while the remaining or inner portion of the flange 54 forms generally a continuation of the flange 47. It will be noted that the flange 54 has outwardly turned ends 55 and 56 that seat against the respective reinforcing strips 40 and 41 and are rigidly secured thereto. Secured to the mounting plate 51 along an edge portion thereof which is co-extensive with the end and bottom walls 25 and 27 of the suitcase is an arcuate L-shaped channel 57 having one leg thereof secured to the face of the plate 51 and the other leg thereof secured to the end and bottom walls 25 and 27 of the suitcase.

The mounting plates 46 and 51 in conjunction with the flanges 47 and 54 thereof and with the reinforcing strips 40 and 41, define a compartment or chamber 58 that is closed except for the channel 39 through which a circumferential portion of the wheel 37 projects. This chamber is sealed along all the edges thereof that lie within the suitcase compartment 14, and thus affords a dust-proof housing containing the wheel 37 and thereby isolating the compartment therefrom and from foreign materials which would soil clothing or other articles contained within the suitcase compartment 14.

The wheel 37 is equipped with a tire 59 that is ornamented with stitch lines 60 and 61 that are respectively aligned with the stitch lines 31 and 32 of the trim band 29. Thus, as is seen most clearly in FIGURE 2 in connection with the wheel 38 and stitch lines 62 and 63 thereof, such stitch lines give the appearance of being continuations of the stitch lines provided by the trim band.

If reference is made to FIGURES 3 and 4, it will be noted that the radius of the wheel 37 (considering the tire 59 as a part thereof) is substantially the same as the radius of curvature of the corner portion of the container or, more particularly, with respect to the radius of curvature of the trim band 29 which, of course, has a slightly greater radius along the outer surface thereof than that of the container walls 25 and 27 along the line of juncture thereof. Further, the rotational axis of the wheel 37 which is the same as the longitudinal axis of the axle 49 is substantially coincident with the origin of the radius of curvature of the corner portion of the container. That is to say, referring to FIGURE 2, the origin of the radius of curvature of the corner portion 35 of the container, which for the present purposes is the radius of curvature of the trim band 29, is located on the side wall 23; and if the axle 49 were extended through the side wall, the longitudinal axis of the axle would contain the origin of such radius of curvature as a point thereon.

Consequently, a portion of the circumferential surface of the wheel 37 projects through the slot 39 for rolling engagement with a support surface, and when in engagement with such surface elevates the walls 25 and 27 along the line of juncture thereof above the support surface as shown in FIGURE 2. Also, since the radii of the wheel and corner portion are coextensive, the exposed surface of the wheel replaces the material removed from the container in forming the slot 39 therein and forms a continuation of the trim band 29 or container corner portion in this area. Therefore, the wheel 37 is incon-

spicuous, and in fact completes the contour of the corner portion. This effect is implemented by equipping the wheel with stitch lines 60 and 61 which are aligned, respectively, with the stitch lines 31 and 32 of the trim band. Another advantage in this construction is that the radius of curvature of the corner portion of a suitcase or similar container is relatively large, whereby wheels of relatively large diameter are provided; and as a result, the rolling action afforded by the wheels is immeasurably superior to the rolling action afforded by casters especially over rough or irregular surfaces. It will be apparent that the same general results can be obtained even though the radius of the wheel 37 is varied somewhat from precise correspondence with the radius of curvature of the corner portion of the container by simply appropriately locating the axis of rotation of the wheel in accordance with the direction and extent of any such variation from correspondence between the two radii.

Modified constructions embodying substantially the same inventive concepts are illustrated in FIGURES 6 through 8, and such modifications will now be described. In the construction shown in FIGURE 6, the suitcase 10a defines a compartment 14a therein, and has an end wall 25a that merges with a bottom wall 27a to define a curved corner portion 35a. The end and bottom walls are secured to a side wall 23a which has an opening therein through which an axle 49a extends, that rotatably supports a wheel 37a disposed exteriorly of the side wall. The axle 49a is carried by a mounting plate 46a that is riveted or otherwise rigidly secured to the side wall 23a of the suitcase. Suitable washers or sealing elements may surround the axle 49a both interiorly and exteriorly of the side wall 23a to maintain the compartment 14a in a dust and dirt-proof condition. The radius of the wheel 37a and the positioning thereof along the side wall 23a with respect to the corner portion 35a is in accordance with the heretofore described embodiment of the invention.

In the modification illustrated in FIGURE 7, the structural composition is identical with the one illustrated in FIGURE 6, but incorporated therein is a cover or shield 64 that substantially encloses the wheel. For convenience, the components illustrated in FIGURE 7, except for the shield 64, are denoted with the numerals adopted to identify the parts shown in FIGURE 6, except that the letter "b" has been used instead of the suffix "a." The cover 64 is equipped with a laterally turned flange 65 that extends along the outer surface of the side wall 23b and is secured thereto by any suitable means. Along the corner portion 35b, the cover 64 has a slot 66 through which a surface portion of the wheel 37b projects. Again, the dimensional relationship of the wheel 37b and curvature of the corner portion 35b are in accordance with the structures heretofore described.

In the modification of FIGURE 8, the suitcase 10c defines a compartment 14c therewithin and has an end wall 25c and bottom wall 27c, both of which are secured to a side wall 23c. The side wall 23c adjacent the corner portion 35c is offset inwardly, as shown at 67, to define a recess or chamber 68 dimensioned to receive the wheel 37c therein. The wheel is mounted upon an axle 49c journaled in a bearing 69 carried by the mounting plate 46c which is riveted or otherwise secured to the recessed wall portion 67 of the side wall 23c. Thus, the compartment 14c is isolated from the exterior by the structural composition of the wheel and axle assembly. The dimensional relationships of the wheel 37c and corner portion 35c are as heretofore described.

While in the foregoing specification embodiments of the invention have been set forth in considerable detail for purposes of making an adequate disclosure thereof, it will be apparent to those skilled in the art that numerous changes may be made therein without departing from the spirit and principles of the invention.

I claim:

1. In combination, a suitcase or the like comprising a pair of cooperative casing sections defining an article-receiving compartment therein and being related to each other for selective opening and closing movements to provide access to such compartment, said suitcase having a pair of transversely spaced side walls, a pair of longitudinally spaced end walls respectively secured to said side walls, and a top wall and a bottom wall each secured to said side and end walls, said bottom wall and at least one of said end walls along the juncture common thereto having an arcuate configuration adjacent each of said side walls defining rounded corner portions thereat having the same radii of curvature, a pair of wheels respectively located adjacent said rounded corner portions in substantially parallel relation with the respectively associated side walls and in close proximity thereto, and a pair of axle structures respectively supported adjacent said rounded corner portions by said casing sections and being constrained against displacements with respect thereto, said axle structures being transversely oriented and defining a condition of axial alignment approximately coincident with a transversely extending line defined by the origins of the radii of curvature of said rounded corner portions when said casing sections are in the closed position thereof, said wheels being respectively mounted upon said axle structures for rotation about the axes thereof and each wheel having a radius essentially equal to the radius of curvature of the associated corner portion to provide the wheel with a restricted circumferential surface area extending radially outwardly only very slightly beyond the dimensional limits of the associated corner portion for rollingly supporting said suitcase but without substantial interference with normal handling and storage thereof.

2. The combination of claim 1 in which each of said wheels is mounted within the interior of the associated suitcase section, and in which each of said suitcase sections is provided with a slot in the rounded corner portion thereof aligned with the associated wheel and passing the aforesaid surface area therethrough.

3. The combination of claim 2 in which each of said suitcase sections is equipped with support structure defining a substantially closed chamber about the associated wheel to isolate the same from the interior of said suitcase.

4. The combination of claim 2 in which said suitcase is equipped with a trim strip along each of the edges of the side walls thereof which extends about said rounded corner portions, and in which each of said trim strips at said rounded corner portions is provided with a slot therein aligned with the slot in the associated corner portion and passing the aforesaid surface area of the associated wheel therethrough.

5. The combination of claim 1 in which the axis of rotation of each of said wheels is coincident with the radius of curvature of the respectively associated corner portions, and in which the radius of each of said wheels is slightly greater than the radius of curvature of the respectively associated corner portions to provide the aforesaid restricted surface areas projecting radially outwardly beyond the dimensional limits of said corner portions.

6. A portable container comprising side walls, end walls and a bottom wall defining a compartment for the receipt of articles therein; said bottom wall and at least one of said end walls along the juncture common thereto defining an arcuate configuration to provide said container with a rounded corner portion adjacent each end of such juncture; the origin of the radius of curvature of each of said rounded corner portions being respectively located at the opposite ends of a transverse line extending through said container in generally parallel relation with a line defined by the juncture of the aforesaid bottom wall and one end wall and terminating at said side walls; and a pair of wheels rotatably supported by said container respectively at said rounded corners in substantially parallel re-

lation with the respectively associated side walls and each of said wheels having a circumferential surface area projecting slightly beyond the dimensional limits of said container at said rounded corner portions for surface engagement to rollingly support said container thereon; the radius of each of said wheels being approximately the same as the radius of each of said corner portions and the axes of rotation of said wheels being generally located along the aforesaid transverse line so that only a restricted surface area of each wheel projects very slightly beyond the associated rounded corner of said container and causes substantially no interference with normal handling and storage thereof.

7. In combination with a container such as a suitcase or the like having rounded corners, a pair of substantially parallel wheels respectively carried by said container adjacent transversely spaced corner portions thereof for rotation about a transversely extending axis to rollingly support said container in at least one position thereof, the radius of curvature of each of said transversely spaced portions and the radius of each of said wheels being substantially the same and the axis of rotation of said wheels being substantially coincident with a transversely extending line defined by the origins of the respective radii of said transversely spaced corner portions so that only a restricted surface area of each wheel projects very slightly beyond the associated rounded corner of said container and causes substantially no interference with normal handling and storage thereof.

8. The combination of claim 7 in which each of said wheels is mounted within the interior of said container, and in which said container is provided with a pair of slots therein respectively aligned with said wheels and passing surface portions of the wheels therethrough to accomplish the aforesaid rolling support of said container.

9. The combination of claim 8 in which said container

is equipped with support structures for the respective wheels defining substantially closed chambers thereabout to isolate the wheels and slots therefor from the interior of said container.

10. In combination with a container such as a suitcase or the like having rounded corner portions and having a trim strip extending along the edge of each such corner portion, said container being provided with a pair of slots respectively located at transversely spaced corner portions thereof in substantial alignment with the trim strip therefor and extending therethrough, a wheel rotatably supported within said container at each of said transversely spaced corner portions in alignment with the slot therethrough and with a surface portion of each wheel extending through such aligned slot for rolling engagement with a support surface, that surface portion of each wheel extending at any instant through the associated slot being effective to complete the surface of the container corner portion and trim strip thereat while maintaining the contour of the rounded corner portion in which the wheel is mounted, whereby only a restricted surface area of each wheel projects very slightly beyond the associated rounded corner of said suitcase and causes substantially no interference with normal handling and storage thereof.
